THEFTPROOF MILK BOTTLE RECEPTACLE

Carl D. Eggebrecht, Bayside, N. Y.

Application January 6, 1937, Serial No. 119,185

2 Claims. (Cl. 232—41)

One object of this invention is the provision of a receptacle adapted to be mounted adjacent a door in the wall of a house or apartment, having an opening on one side of its front wall through which milk bottles may be inserted into the receptacle, and another opening through its inside wall through which the bottles may be removed from the receptacle, with means provided for preventing removal of the bottles from the outside opening after they have once been inserted and positioned within the receptacle.

Another object of the invention is the provision of a receptacle, the front wall of which is adapted to be mounted flush with the outside wall of the apartment, having a semi-cylindrical extension projecting beyond this wall, in which a turnstile is mounted, the turnstile being rotated through a quadrant upon pushing a bottle from this extension into the receptacle, the turnstile being rotatable in one direction only so that the bottle once inserted in the receptacle cannot be removed through the turnstile.

The above and other objects will become apparent in the description below, in which characters of reference refer to like-named parts in the accompanying drawing.

Referring briefly to the drawing, Figure 1 is a front elevational view, illustrating the device mounted in the wall of a dwelling.

Figure 2 is a cross-sectional view taken on the line 2—2 of Figure 1.

Figure 3 is a cross-sectional view taken on the line 3—3 of Figure 2.

Figure 4 is a cross-sectional view taken on the line 4—4 of Figure 3.

Figure 5 is a perspective view of the receptacle per se.

Referring in detail to the drawing, the numeral 10 indicates the outer wall of an apartment or dwelling. An opening is provided at the bottom of the wall for insertion therein of a receptacle 11 having its front wall 12 flush with the outside of the wall 10 and its rear wall 13 lying adjacent the inside of the wall 10 in the interior of the apartment, and, if desired, flush with the inside wall. A semi-cylindrical projection 14, enclosing a vestibule 20, is provided at one end of the wall 12 of the receptacle, and a sliding door 15 having a handle 16 is adapted to open or close an opening into the vestibule 20.

A turnstile is vertically mounted in the projection 14 on a pivot post 17. Vertically aligned horizontal prongs 18, extending rigidly from a sleeve 19 rotatable on the post 17, divide the turnstile into a plurality of vertical compartments,

or, as illustrated, quadrants. A ratchet 19a is rotatably mounted on the post 17 near the floor 21 of the receptacle 11, and a pawl 22 lies in engagement therewith to permit rotation of the turnstile in one direction only, that is, in a counter-clockwise direction, Figures 2 and 4.

A plurality of transverse rollers 23 are mounted as a spaced-apart distance above the floor 21. A platform 24 is mounted at the bottom of the projection 14 at the same distance above the floor 21. A platform 24 is supported on its outer end on an upright 25, extending rigidly from the floor 21. The opposite end of the platform 24 is provided with a depending web 26. The web 26 is extended along the front side of the compartment 27 within the receptacle, and is elongated over the distance from the left-hand (Figure 2) end of the vestibule 20, to the left-hand end of the compartment 27, to extend from the floor 21. Thus, the entire length of the web 26 serves as a support for one end of each of the rollers 23. The opposite ends of these rollers are supported in an upright strip 28 extending rigidly from the floor 21. In the rear wall 13 of the receptacle, a hinged door 29 having a handle 30 is provided, by means of which the bottles may be removed from the receptacle within the compartment.

The operation of the device is as follows: The door 15 is normally closed, as shown in Figure 5. To insert a bottle into the receptacle, the door 15 is first slid open, a bottle is inserted into the vestibule 20 and pushed inward toward the receptacle. The bottle will then lie within the upper right-hand quadrant of the turnstile, Figure 2. If now a second bottle is inserted, the turnstile will carry the first bottle, first toward the rear wall of the receptacle, and thence, from left to right along the compartment 27, riding on the rollers 23. In this manner a large number of bottles may be inserted into the receptacle. To prevent an inserted bottle from being carried back into the vestibule 20 by continued rotation of the turnstile, a series of rigid check prongs 31 are mounted on the inside of the wall 12 and project into the spaces between the orbits of the turnstile prongs 18. It is impossible for the bottles to be removed from the outside of the wall 10 through the projection 14, because of the above-mentioned locking of the turnstile against rotation in the opposite direction. It is thus apparent that a theft-proof receptacle has been provided which is a guarantee against removal of the bottles by unauthorized persons.

Obviously, modifications in form and struc-

ture may be made without departing from the spirit and scope of the invention.

I claim:

1. A receptacle comprising a housing adapted to be mounted in a wall of a building, the front wall of said housing having at one end of said housing a semi-cylindrical projection extending outward therefrom, a turnstile mounted in said projection, a door in said projection, rollers mounted transversely adjacent the floor of the receptacle, means cooperating with said turnstile to permit rotation thereof in one direction and to prevent rotation in the opposite direction, a platform mounted adjacent the bottom of said projection under the forward end of said turnstile on the same level as said rollers, and prongs on said front wall and projecting substantially parallel therewith into the orbit of said turnstile.
- 15 2. A receptacle comprising a substantially rec-

tangular housing adapted to be mounted in a wall of a building, a turnstile mounted in one end of the front wall of said housing, an opening in said housing into said turnstile, rollers mounted transversely adjacent the floor of the receptacle, 5 means cooperating with said turnstile to permit rotation thereof in one direction and to prevent rotation in the opposite direction, a platform mounted adjacent the bottom of said housing on the same level as said rollers on one side of said turnstile, and means mounted between said receptacle and said projection for guiding a bottle which has been inserted into the receptacle away from said turnstile, said means comprising 10 prongs secured at one end to the front wall of said housing and projecting substantially parallel with said front wall into the orbit of said turnstile.

CARL D. EGGBRECHT.
